[57] CLAIM

The ornamental design for a blood pressure monitor, as shown and described.

DESCRIPTION

FIG. 1 is a perspective view of a blood pressure monitor, showing my new design, with the lid in closed position;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof; and,

FIG. 8 is a perspective view thereof with the lid in open position, the broken line showing is for illustrative purposes only and forming no part of the claimed design.

FIG. 1

FIG. 2

FIG. 3

FIG. 4

FIG.5

FIG.6

FIG.7

FIG. 8
